UNITED STATES PATENT OFFICE

160,021

HANDBAG OR SIMILAR ARTICLE

Aaron Rothchild, Flushing, N. Y.

Application September 6, 1949, Serial No. 4,869

Term of patent 7 years

(Cl. D87—3)

To all whom it may concern:

Be it known that I, Aaron Rothchild, a citizen of the United States, residing at Flushing, in the county of Queens and State of New York, have invented a new, original, and ornamental Design for a Handbag or Similar Article, of which the following is a specification; reference being had to the accompanying drawing, forming part thereof.

Fig. 1 is a front elevational view of a handbag or similar article, showing my new design.

Fig. 2 is an edge view thereof taken from the left of Fig. 1.

Fig. 3 is an edge view taken from the right of Fig. 1, with a portion of the chain broken away for convenience of illustration.

Fig. 4 is a rear elevation of the handbag.

Fig. 5 is a top view of the handbag as shown in Fig. 1.

Fig. 6 is a bottom view thereof.

Fig. 7 is a plan view of the handbag in an open position, a portion of the chain being broken away for convenience of illustration as in Fig. 3.

I claim:

The ornamental design for a handbag or similar article, substantially as shown.

AARON ROTHCHILD.
